UNITED STATES PATENT OFFICE.

HENRY A. BUDDE, OF MANCHESTER, CONNECTICUT.

DESIGN FOR A CASING FOR HYDROCARBON-ENGINES.

46,467.

Specification for Design.

Patented Sept. 29, 1914.

Application filed May 15, 1914. Serial No. 838,882. Term of patent 14 years.

To all whom it may concern:

Be it known that I, HENRY A. BUDDE, a citizen of the United States, residing at Manchester, county of Hartford, and State of Connecticut, have invented a new, original, and ornamental Design for a Casing for Hydrocarbon-Engines, of which the following is a specification, reference being had to the accompanying drawings, forming a part thereof, and in which—

Figure 1 is a front elevation and Fig. 2 a

side elevation as seen from the right in Fig. 1, of a hydrocarbon engine showing my new design.

I claim:

The ornamental design for a casing for hydrocarbon engines as shown.

HENRY A. BUDDE.

Witnesses:

CHARLES R. LEWIS,
JOSIE A. SULLIVAN.
